VOLTAGE REGULATOR

Pierre Marie Gabriel Toulon, Paris, France, assignor to Products & Licensing Corporation, New York, N. Y., a corporation of Delaware

Application May 16, 1949, Serial No. 93,614
In France May 25, 1948

8 Claims. (Cl. 321—38)

1

The present invention relates to a new system for stabilizing the amplitude of an alternating voltage, offering the advantages of being, on the one hand, very powerful, and on the other hand, of assuring a very precise regulation. It applies more especially to the stabilization of the voltage at the terminals of an oscillating circuit connected with a driving circuit.

Voltage regulators usually employed heretofore have been, in general, of two kinds, those utilizing a rectifier, appropriately polarized to enable initiation of current flow when the voltage of the circuit surpassed a certain limiting value, equal generally to that of the polarizing source, and those utilizing a gas tube (such as a neon tube), which fires at a predetermined threshold voltage. These devices are usually combined with a resistance, disposed in series with the circuit, and the current which flows in the resistance brings about a fall in voltage in that resistance, which opposes the accidental and undesired variations in voltage at the terminals of the circuit. However, voltage regulation systems of this character are neither powerful nor precise, since the resistance values have to have values selected to maintain satisfactory efficiency, and the voltage which appears across the resistance does not precisely compensate for the variation which is to be annulled. Gaseous tubes present, besides, the disadvantage of being unstable in respect to firing voltage, of being dependant upon temperature conditions, of being subject to aging, and finally of passing a current which varies according to the voltage applied to the tube, which facts render the regulation obtainable imperfect.

All of these disadvantages are avoided by the present invention, which assures a flexible adjustment, and one which is automatic, very precise, very powerful, and positive in operation.

According to the invention, I dispose between the terminals of a circuit receiving an alternating voltage whose amplitude is subject to accidental variations which are to be regulated, an automatic restrictor, the functioning threshold of which is selected in such a way that it does not respond to these variations. I amplify the voltage to be regulated by means of an electronic tube circuit. I combine in the output circuit of the amplifier the amplified alternating voltage, with a rigorously constant voltage, such as that of a battery, in such a way as to produce a current which is a function of the relative values of the two voltages. I cause this current to react, by the means of an appropriate coupling, on the input circuit of the amplifier, in such a way as

to lower the response threshold of the resistor which is disposed in the latter. I cause the latter, thereby, to begin to operate, in such a way as to reduce the accidental variations in voltage, which are found thereby to be limited at a practically constant level.

The invention comprises various specific embodiments. The restrictor in the input circuit may consist of a rectifier in series with a polarizing source, which may be a battery, which normally blocks the rectifier, and which is selected in such a way that it remains insensitive to a certain margin of increase of input signal. The means of comparison in the output circuit may likewise comprise a rectifier in series with a blocking battery. The latter is selected to have a value such that any increase in voltage above a desired value causes current flow through the rectifier. The current thus produced brings about, in combination with a circuit, having an appropriate time constant, a continuous slowly varying difference in potential, which is applied to the input restrictor, by the intermediary of a feedback circuit, preferably provided with means for blocking the input signal; this difference in potential controls the voltage variation in the input circuit. It is introduced in series with the rectifier in the input circuit, in opposition to the blocking battery. The operating threshold of the rectifier is thus greatly lowered, and the current which it passes then brings about a fall in voltage in a resistance disposed in series with the input circuit, absorbing the accidental variation.

35 The invention is more especially interesting in the case of existing systems comprising amplifiers connected with oscillating circuits, in which case the present system can be applied to the existing amplifiers.

40 The invention will be better understood by reference to the accompanying drawings, wherein:

Figure 1 is a schematic circuit diagram, in accordance with the invention, wherein regulation is accomplished of voltage furnished by an oscillating circuit, an input restrictor and output regulator being employed, which are each of the biased rectifier type;

Figure 2 represents operating characteristics of the system of Figure 1, provided purely for purposes of simplifying the explanation of the operation of the system.

In Figure 1, I have shown at 1—2 the terminals of a conventional generator of alternating current, G, represented as an oscillating triode,

2

with a feed back circuit. It is assumed that the power furnished by it is to supply a load, which may be connected to terminals 3, 4, via an amplifying tube 5, having an anode supply 6, a grid 7, an anode 8, a cathode 9, and a coil 10 in the anode circuit coupled to an oscillating circuit, across which are connected terminals 3, 4. The problem which the present invention proposes to solve is to stabilize in a very precise fashion, the amplitude of the alternating voltage at the terminals 3, 4.

This result is obtained by a feedback process. I connect in series between the terminal 4 and the grid 7 of the amplifier, a resistance R. Terminal 2 is connected to the cathode 9. Connected from grid 7 to cathode 9 is a rectifier 12, in series with a battery 13, and a resistance 14 shunted by a condenser 15. The battery 13 is poled to oppose the passage of current in the rectifier 12, its positive pole being connected to the cathodic terminal thereof. Across the oscillating circuit 11, and hence across the terminals 3, 4, is a further rectifier 16, in series with a battery 17 and a resistance 18 shunted by a condenser 19. The battery 17 is poled in such a way as to block or off-bias the rectifier 16. The voltage at the terminals of the condenser 19 is applied to condenser 15 via a coil 20, which passes the D.-C. component of any voltage present across condenser 19, without transmitting the alternating or signal component of that voltage. The condenser 15 thus acquires a voltage the polarity of which is indicated in Figure 1, and which is opposed to that of the battery 13.

Figure 2 represents, as a function of time, the voltages which appear in the different parts of the system of Figure 1, and assists in facilitating understanding of the general operation of the system. It is to be understood that Figure 2 provides only an approximate illustration of this operation, and is only given here as exemplary, and to assist in comprehension of the disclosure. The first curve represents, as a function of time, the voltage which appears between terminals 22, 23, connected between grid 7 and cathode 9, and which represents the input signal to the amplifier 5. The left half of curve 21 corresponds to the voltage actually present at the terminals 22, 23. The right half, at 24 (above the dotted lines), cannot exist precisely because of the operation of the regulator system, i. e., is the voltage which would exist were the regulator system absent. The second curve, 25, shows the actual form of the voltage applied to the grid of tube 5, in consequence of the simultaneous intervention of the amplitude regulating device, and of the presence of the oscillating voltage provided by the generator G.

The third curve, 26, represents the voltage at the output terminals 3, 4, that is to say after amplification by the tube 5.

At the beginning of the operation, the condenser 15 is not charged. The generator G, beginning to oscillate, impresses an alternating voltage on the input terminals 22, 23 of the amplifier tube 5. It is assumed that this voltage increases progressively. If no other phenomenon existed the rectifier 16 would eventually pass current. This would produce peaks, as at 24, when the maxima of the curve 21 surpass the horizontal line 2-2', traced at a distance corresponding to the voltage P of the battery 13. This system of regulation is that taught in the prior art, but is not very precise, and hence is not very satisfactory. According to the present invention, I in-

crease enormously the sensitivity of the regulator, thanks to the feedback circuit, described herein-after. I so select the coefficient of amplification of the tube 5, the voltage of the bias battery 17 and the voltage of the bias battery 13, that the rectifier 16 begins to pass current before the rectifier 12 does, and as soon as the maximum of the alternating voltage 26 appearing in the oscillating output circuit 11 becomes greater than the voltage of the bias battery 17 (represented in Figure 2 by the horizontal line V-V'). At this voltage, the rectifier 16 begins to pass current, represented by the shaded portions 27, which brings about a relatively large fall in voltage across the resistance 18, and causes the condenser 19 to charge.

I have represented, on the fourth line of Figure 2, the voltage 28 which appears across the condenser 12, as a function of time. As soon as the voltage 26 rises above the horizontal line V-V', a voltage 28 appears on the condenser 19. This voltage is transmitted to the condenser 15, which diminishes the effect of the bias voltage of battery 13 on the rectifier 12. In Figure 2, we have taken this effect into account, by plotting the curve 28 against the line 2-2', which represents the voltage of battery 13. We construct thereby a curve 29 exactly like the curve 28, but inverted.

The voltage at the terminals 22, 23, is found to be limited to the shaded part situated below the curve 29. The voltage thereby obtained would correspond to that which would exist on the grid 7 of the tube 5, if no oscillating circuit existed in the circuit of the generator G, but the presence of this oscillating circuit has the effect of rendering all the voltages sinusoidal. The rectifier 12 thus exercises only an attenuating effect on the oscillating circuit, reducing the amplitude of the oscillations in the circuit G. The voltage 25, which is approximately a sinusoid, having the curve 29 as an envelope, represents approximately the voltage which is actually applied to the grid of tube 5. The voltage 25, which is zero when oscillator G commences operation, begins thus to increase until it attains the amplitude 30. Beginning with this moment the rectifier 16 begins to function, which induces, as illustrated at 31, an abrupt reduction in amplitude. The amplified voltage at the output undergoes the same variations. As a result, during some alternations of voltage, for example those below lines 2-2' in Figure 2, the rectifier 16 no longer exercises its effect, because the voltage has not yet disappeared from the condenser 19. But after a few alternations, as at 27, when the voltage of the condenser 19 has been sufficiently reduced, the rectifier 16 passes current again, causing again an increase of voltage at the terminals of the condenser 19. This effects again a rapid reduction of amplitude, and the process continues in this manner. After a few oscillations, the signal amplitude at the output terminals 3, 4 is maintained at an extremely precise value, because the slightest flow of current via rectifier 16 has the effect of modifying in a very rapid manner the voltage of the condenser 19. We understand that the sensitivity of the circuit is considerably increased by the amplification of tube 5. The voltage at the terminals 22, 23 is found thereby to be stabilized, and tube 5 now only furnishes a continuously controlled power. The voltage ceases to increase at the terminals 3, 4 and is rigorously stabilized.

This stabilization is extremely precise by rea-

son of the fact that the coefficient of amplification of the tube is generally very great. For example, the voltage of the battery 13 is of the order of 1 volt, and the voltage of the battery 17 is of the order of 500 volts. Suppose, for example, that the amplitude of the alternating voltage at terminals 3, 4, surpasses the voltage of the battery 17, if only by 0.5 volt (for example, $1/1000$ of its value), the voltage engendered on the resistance 18 is of the same order of greatness, or slightly less, say 0.4 volt; this voltage, in part transferred to the condenser 15 induces therein a slightly weaker voltage, but of the same order of magnitude, say 0.3. The amplitude of the voltage at 22, 23, which was 1 volt, is therefore reduced to $1-0.3=0.7$ volt. It thus appears that the power furnished by tube 5 is reduced to about 30% of its value. The regulating effect is thus enormous. In actuality such large variations have no chance of being produced, even in passing abruptly from operation with no output to full output, that is to say, the stabilization is extremely perfect. It would not have been the same with a regulator arranged in the conventional manner, because the variation of voltage at the input would have been only $1/1000$ of its value instead of $300/1000$.

While I have described and illustrated a specific form of the invention it will be clear that variations thereof may be resorted to without departing from the true scope of the invention as defined in the appended claims.

What I claim and desire to secure by Letters Patent of the United States is:

1. An amplitude regulator for periodic voltages, comprising, a source of oscillations, a vacuum tube amplifier having an input circuit and an output circuit, a voltage dropping resistance connected in series between said source of oscillations and said input circuit, a biased rectifier connected across said output circuit, and means responsive to current flow in said rectifier for controlling voltage drop in said voltage dropping resistance.

2. An amplitude regulator for periodic voltages, comprising, a source of oscillations, a vacuum tube amplifier having an input circuit and an output circuit, a voltage dropping resistance connected in series between said source of oscillations and said input circuit, a rectifier biased in one polarity connected in series with a condenser across said output circuit, an oppositely biased rectifier connected in series with a condenser across said input circuit, means responsive to voltage across said first named condenser for reducing bias of said oppositely biased rectifier by charging said last named condenser, and means responsive to current flow in said oppositely biased rectifier for controlling voltage drop in said voltage dropping resistance.

3. An amplitude regulator for periodic voltages, comprising, a source of oscillations, a vacuum tube amplifier having a cathode, an anode, and a control electrode, a voltage dropping resistor, means connecting said source of oscillations in series with said voltage dropping resistor, means connecting said cathode and control electrode across said source of oscillations and said resistor connected in series, with said control electrode connected to a terminal of said resistor, a rectifier having an anodic terminal, a source of voltage, a condenser, means connecting said rectifier, said source of voltage and said condenser in series

between said cathode and said control electrode, said anodic terminal being connected to said terminal of said resistor and with said source of voltage poled to bias said rectifier against current flow, an output circuit coupled to said amplifier, and means for controlling voltage across said condenser in response to voltage across said output circuit.

4. In a voltage regulator, a source of oscillations, an amplifier having an input circuit and an output circuit, a rectifier and means for providing a variable bias for said rectifier connected in series across said input circuit, whereby current flow in said rectifier is responsive to said variable bias, and means responsive to voltage across said output circuit for determining said variable bias.

5. In a voltage regulator, a source of oscillations, an amplifier having an input circuit and an output circuit, a rectifier circuit having a fixed direct current bias and a variable direct current bias opposing said fixed direct current bias, said rectifier circuit connected in shunt to said input circuit, and means responsive to deviations from a predetermined value of voltage in said output circuit for varying said variable direct current bias.

6. In a voltage regulator, a source of oscillations, an amplifier having an input circuit and an output circuit, means coupling said input circuit to said source of oscillations a rectifier having a fixed D.-C. bias and a variable D.-C. bias opposing said fixed D.-C. bias, said rectifier connected in shunt to said input circuit, a rectifier circuit coupled to said output circuit and comprising a source of bias voltage for preventing current flow in said rectifier circuit in response to voltage of less than a predetermined magnitude, and means responsive to said current flow for determining said variable D.-C. bias.

7. The combination in accordance with claim 6 wherein said means responsive to said current flow comprises a condenser connected in series with said rectifier and said source of bias voltage, a discharge resistance shunting said condenser, and means responsive to average voltage across said condenser for establishing said variable D.-C. bias.

8. An amplitude regulator for periodic voltages, comprising, a source of periodic voltages comprising an oscillating circuit, a rectifier shunting at least part of said oscillating circuit, means for biasing said rectifier against passage of current therethrough, said means for biasing comprising a source of constant direct current voltage and a source of variable direct current voltage opposing said constant direct current voltage, means for amplifying said periodic voltages to provide amplified signals, and means responsive to said amplified signals for controlling the magnitude of said variable direct current voltage.
